UNITED STATES PATENT OFFICE.

JOHN HICKS, OF CALGARY, ALBERTA, CANADA.

ORE-SEPARATOR.

1,346,824.

Specification of Letters Patent. Patented July 20, 1920.

Application filed May 29, 1918. Serial No. 237,300.

To all whom it may concern:

Be it known that I, JOHN HICKS, a subject of the King of Great Britain, residing at Calgary, in the Province of Alberta and Dominion of Canada, have invented new and useful Improvements in Ore-Separators, of which the following is a specification.

This invention is an improved ore separating apparatus especially adapted for use in recovering flour gold and fine gold particles from gold bearing sands and deposits such as black sands and gravel found in the beds of streams, the object of the invention being to provide an improved apparatus of this kind which is simple in construction and which embodies means to employ the compressed air, steam or other fluid medium under compression to set up whirling motion in the sands as they pass through a conduit and to also effect a separation of the sands and a recombining or mixing thereof as they pass through said conduit, so that all the sand particles are subjected to attrition and are moistened or wet to cause the flour gold to be effectually separated from the sands; the invention also embodying a mercury cup or vessel into which the separated ore particles, gold, sand and the like, are driven while still whirling so that said ore particles also set up whirling motion in the mercury with the result that the flour gold particles are caused to settle and become collected in the mercury in the cup while the sands and other worthless particles, which are lighter, are whirled off the face of the mercury and out of the mercury cup and are discharged, and without forcing the mercury out of the cup.

With the above and other objects in view, the invention consists in the construction, combination and arrangement of devices hereinafter described and claimed.

In the accompanying drawings:—

Figure 1 is a vertical sectional view of an ore separating apparatus constructed and arranged in accordance with my invention.

Fig. 2 is a transverse sectional view of the same, on a larger scale, on the plane indicated by the line 2—2 of Fig. 1.

Fig. 3 is a similar view on the plane indicated by the line 3—3 of Fig. 1.

Fig. 4 is a detail sectional view, on a larger

scale, of the mixing element and its connections.

Fig. 5 is a similar view of the mercury cup. 55

Fig. 6 is a vertical sectional view showing a modification in the construction of the mixing element and its connections.

A vertical pipe 1 is provided at its upper end with a feed hopper 2 and is arranged to discharge at its lower end into a mercury cup 3 which mercury cup is held by a cross bar 4 or other suitable support in a box 5, the box having a door 6 in one side to afford access to the mercury cup and being provided at the bottom, below the mercury cup, with a tailings discharge 7. The mercury cup is open in the upper side and has a pocket 8 at the bottom and also has a valve 9. The wall 10 of the mercury cup is flared outwardly and upwardly and is doubled inwardly and downwardly as at 11, to form an annular expansion chamber 12 which extends around the cup. A partition wall 13 is arranged in the cup and spaced from the wall thereof, the upper portion of the partition wall being flared outwardly and upwardly and extending into the expansion chamber 12. Said partition wall is provided with perforations 14. 60 65 70 75 80

A steam pipe 15 leads from a suitable boiler into the lower portion of the pipe 1 and is provided with a downwardly directed nozzle, elbow or rose 16 which discharges down through the pipe 1 and into the mercury cup. The lower section 17 of the pipe 1 is secured in an opening in the bottom 18 of a drum 19 and the upper section 20 of said pipe is secured in an opening in the top of the drum. The drum is secured to the bottom by bolts 21. The upper pipe section 20 has an air inlet opening 22 in one side. Cross bars 23 are arranged in the lower portion of the pipe section 20 and at a point slightly above the drum. 85 90 95

A mixing element 24 is here shown as a vertical hollow tubular member which is arranged in the drum 19 and the inner diameter of which corresponds with that of the pipe 1 and the axis of said mixing element being coincident with that of the pipe. The inner wall 25 of the mixing element 24 is provided with tangentially arranged perforations 26 and also with upwardly inclined perforations 100 105

27 and inwardly inclined perforations 27^a. A pipe 28 which leads from a source of water or a source of compressed air is connected to the mixing element 24 and is provided with a cut-off valve 29. A branch pipe 30 leads upwardly from the pipe 28, is provided with a cut-off valve 31 and terminates at its upper end in an upwardly directed nozzle 32 which discharges upwardly into 10 the lower end of the hopper 2. The hopper also has a suitable feed valve 33 to regulate the supply of gold sands to the upper end of the pipe 1.

In the operation of the invention the gold bearing sands are fed from a tank to the hopper and from the hopper to the upper end of the pipe 1. The jet of water, compressed air or other fluid from the nozzle 32 prevents the sands from choking in the 20 throat of the hopper and the sands drop through the pipe 1. As the sands drop through said pipe they strike and their mass is broken by the cross bars 23 and as the sands pass through the mixing element 24 they are caught by the tangential jets of water or compressed air which are discharged through the tangential perforations 26 and are whirled thereby around and around in the separator and are also caught 30 by the upwardly inclined and inwardly directed jets of water or compressed air from the perforations 27 so that the passage of the sands downwardly through the mixing element is somewhat retarded, so that between said upwardly directed jets and the said tangentially directed jets the sands are thoroughly separated into particles and are dashed against the sides of the separator and each particle of the sands 40 and of flour gold is moreover thoroughly wetted by the streams or jets of water, when water is employed. The whirling of the sands continues as the sands pass down through the lower section 17 of the pipe 45 and while passing therethrough the sands alternately strike the wall of the pipe and rebound toward the center thereof so that a complete separation and mixture of the sands is effected. As the whirling sands 50 near the lower discharge end of the pipe 1 they are caught by the downwardly directed jets of steam from the nozzle 16 of the steam pipe 15 and are forcibly and while still whirling driven down into the mercury cup and are caused to whirl also in the mercury cup. The fine particles of gold sink through the mercury and are retained there-in in the cup and the sand and water is 60 whirled off the surface of the mercury and out of the mercury cup but without forcing any of the mercury out of the cup.

Owing to the provision of the annular expansion chamber in the wall of the mercury cup any extra pressure from the separator 65 is taken up by the mercury, the mercury ex-

panding into the expansion chamber, as will be understood. A valve 34 is screwed in the bottom of the mercury cup and a bottle 35 is screwed into said valve to take out the gold dust without disturbing the 70 mercury in the cup.

The pipe 28 is connected to a manifold 28^x, and the drum 19 about the upright pipe 1 is divided by annular partitions 60 into annular chambers 61, each of which is in 75 communication with one series of the plurality of series of apertures in the upright pipe 1. Communication between the manifold 28^x and each of the chambers 61 is controlled by a valve 62. By virtue of this 80 provision, the fluid under pressure may be let into the pipe 1 through any one or more series of apertures according to the character of the agitation to which the operator desires to subject the sands. It will also 85 be apparent by comparison of Figs. 1 and 6, that the modification shown in the latter figure and hereinafter described, includes all of the features just defined.

In Fig. 6 I show a modification in the 90 construction of my separator in which the mixing element 24^a is divided by horizontally arranged annular partitions 36 into annular chambers 37, 38. The inner walls of the annular chambers are provided some 95 with tangentially arranged apertures 39 and others with inclined apertures 40 and the upper chambers 37 are connected together by a duct 41 which is formed on one side of the mixer, the lower chambers 38 being 100 connected together by a duct 42. A water supply pipe 43 is connected to the duct 41 and is provided with a cut-off valve 44. A steam or compressed air pipe 45 is connected to the duct 42 and has a cut-off 105 valve 46. Controlling valves 47 are provided for the upper chambers and controlling valves 48 are provided for the lower chambers.

In this construction the sands as they 110 fall through the duct or pipe and through the mixing element are subjected to the action of tangentially arranged water jets and upwardly inclined water jets and are also subjected as they pass through the 115 lower portion of the mixer to correspondingly directed steam or compressed air jets so that a thorough mixing, separating, and whirling of the sands is effected.

While I have herein shown and described 120 preferred embodiments of my invention, I would have it understood that changes may be made in the form, proportion and construction of the several parts, without departing from the spirit of my invention and 125 within the scope of the appended claim.

Having thus described my invention, I claim:—

In an ore separating apparatus, a mercury cup adapted to receive sands from a 130

conduit and having a detachable pocket at its lower end and a valve above said pocket and also having a flared upper portion, said upper portion including an outer wall 5 doubled inwardly and downwardly and forming an annular expansion chamber in the uppermost and outermost portion of the

cup and also including an apertured partition wall spaced from the outer wall and the inner downwardly-extending portion of 10 said outer wall.

In testimony whereof I affix my signature.

JOHN HICKS.
